UNITED STATES PATENT OFFICE.

ZENO BURCH, OF EL CENTRO, CALIFORNIA.

ACCORDION REED-BOX.

1,311,752.

Specification of Letters Patent. Patented July 29, 1919.

Application filed November 20, 1916. Serial No. 132,430.

To all whom it may concern:

Be it known that I, ZENO BURCH, a citizen of Switzerland, residing at El Centro, in the county of Imperial and State of California, have invented certain new and useful Improvements in Accordion Reed-Boxes, of which the following is a specification.

The present invention relates to improvements in reed boxes for accordions and the 10 primary object of my invention is to provide a new and improved type of reed box for use in connection with accordions whereby to make more durable the structure of the reed box, to render the same more easily 15 applicable to an operative position and to provide for the utilization of a plurality of reeds and thus amplify the tone of an accordion.

Another object of my invention is to provide 20 a reed box having a novel construction, preferably of metal, and adapted for application to the accordions as now designed without materially altering the structure of the accordion itself.

25 Other objects and advantages to be derived from the use of my improved reed box for accordions will appear from the following detailed description and the claims, taken with an inspection of the accompanying drawing, in which:

Figure 1 is a fragmental sectional view of an accordion showing a plurality of reed boxes applied thereto;

Fig. 2 is an enlarged perspective view of 35 a reed box embodying the improvements of my invention; and

Fig. 3 is a similar view of one section of the reed box of my invention.

Referring more particularly to the drawing, wherein similar characters of reference 40 designate like and corresponding parts throughout the various views, 10 designates the head of an accordion and 11 the sound-plate. Side walls 12 are connected with the head 10 and serve to form a chamber 13 communicating with the bellows 14. A plurality of valve rods 15 of any standard construction are shown.

A plurality of reed boxes embodying the 50 improvements of my invention are shown mounted on the plate 11, said boxes being designated B in their entireties.

Referring to the detail structure of the reed boxes, which latter is best shown in 55 Figs. 2 and 3, I provide a reed box including two detachable sections, S and S'. The

sections S and S' are preferably V-shaped so that when said sections are joined a substantially rectangular box is provided. Referring to the section S, the same is formed 60 with side walls 16 arranged at right-angles to each other and provided with openings 17 in which the reeds 35 are arranged, as shown on the uppermost reed box in Fig. 1. The walls 16 are provided with base flanges 65 18 to afford securement of the section S' to a plate, said walls also being provided with a plurality of perforations 19 adjacent the free margins thereof to facilitate connection of the sections S and S'. 70

The section S is provided with a half-top portion 20 formed with an upstanding flange 21 provided with perforations 22. The section S' is provided with side walls 24 arranged preferably at right-angles similar 75 to the walls 16 of the section S, said walls 24 being provided with base flanges 25, said base flanges having perforations 26 therein to facilitate securement of the sections to the sound-board 11. The walls 24 80 are provided with a plurality of elongated openings 27 to receive reeds. The free margins of the walls 24 are provided with flanges 28, said flanges being provided with perforations complementary to the perforations 19 in the walls 16, in order that rivets 85 29 or the like may be inserted therethrough to connect the sections together.

The section S is provided with a half top portion 30 formed with an upstanding flange 31 said flange being perforated 90 complementary to the flange 21 to connect the top portions 12 of the sections S and S'.

In use the reed boxes are applied as shown in Fig. 1 and, as in the usual construction 95 of accordion, when the valves are open air is permitted to pass through the reed boxes, vibrating the reeds and producing the music. It will be readily apparent that the construction of my improved reed box facilitates 100 repair of the accordion. The sections from which the reed boxes are formed may be cheaply constructed and owing to the similarity in shape of all the sections the same may be arranged in nested relation 105 and thus readily packed for shipment.

From the above description taken in connection with the accompanying drawing, it is thought that a clear and comprehensive understanding of the construction, operation 110 and advantages of my invention may be had, and while I have shown and de-

scribed the device as embodying a specific structure, I desire that it be understood that such changes may be made in said structure as do not depart from the spirit and scope 5 of the invention as claimed.

Having thus fully described my invention, what I claim as new and desire to secure by Letters Patent, is:—

1. A reed box for accordions, including a 10 pair of sections right-angular in cross section arranged together to provide a rectangular body, said sections each having a plurality of openings therein for receiving a plurality of reeds, and detachably connected 15 flanges carried by the sections.
2. A reed box for accordions, including a 20 pair of sections right-angular in cross section and arranged together to provide a rectangular body, said sections having a plurality of openings therein for receiving a

plurality of reeds, complementary flanges detachably connecting the sections, and base flanges carried by the sections attachable to the accordion.

3. A reed box for accordions, including a 25 pair of detachably connected sections each including apertured side walls and a top portion, and base flanges carried by the sections.

4. A reed box for accordions, including a 30 pair of sections arranged together to provide a rectangular body, said sections being detachably connected along adjacent edges, detachably connected end wall portions carried by the sections, and base flanges carried 35 by the sections.

In testimony whereof, I affix my signature hereto.

ZENO BURCH.
